CLOCK

Rudolph M. Babel, Pawtucket, R. I., assignor to General Electric Company, a corporation of New York

Application August 26, 1953, Serial No. 26,590

Term of patent 14 years

(Cl. D42—7)

Fig. 1.

Fig. 2.

To all whom it may concern:

Be it known that I, Rudolph M. Babel, have invented a new, original, and ornamental Design for a Clock, of which the following is a specification, reference being had to the accompanying drawing, forming a part hereof.

In the drawing, Fig. 1 is a front perspective view of a clock embodying my new design, and Fig. 2 is a side elevational view of the clock shown in Fig. 1.

Both sides of the clock are substantially the same in appearance and the back is conventionally plain aside from the edges of the fluting.

I claim:

The ornamental design for a clock, as shown, and described.
